Primary Examiner — Wan Laymon(74) *Attorney, Agent, or Firm* — Cynthia R. Miller**CLAIM**

The ornamental design for a fragrance bottle, substantially as shown and described.

DESCRIPTION

FIG. 1 is a top, left side and front perspective view of a fragrance bottle showing our new design;

FIG. 2 is a front elevational view thereof;

FIG. 3 is a left side elevational view thereof;

FIG. 4 is a top plan view thereof; and,

FIG. 5 is a bottom plan view thereof.

The broken lines and the areas within the broken lines shown in the figures form no part of the claimed design.
